United States Patent

Des. 239,521
Patented Apr. 13, 1976

239,521

PALLET

Charles E. Griffin, Jr., High Point, N.C., assignor to
Burlington Industries, Inc., Greensboro, N.C.

Filed Oct. 18, 1974, Ser. No. 516,274

Term of patent 14 years

Int. Cl. D9—99

U.S. Cl. D12—53

Fig. 1.

Fig. 4.

Fig. 2.

Fig. 3.

Fig. 5.

Fig. 6.

Fig. 7.

FIG. 1 is a top plan view of a pallet showing my new design;

FIG. 2 is a bottom plan view thereof;

FIG. 3 is a cross-sectional view taken along line 3—3 in FIG. 1;

FIG. 4 is a side elevational view thereof as viewed from the bottom in FIG. 1;

FIG. 5 is a side elevational view thereof as viewed from the top in FIG. 1;

FIG. 6 is a side elevational view thereof as viewed from the left in FIG. 1; and

FIG. 7 is a side elevational view thereof as viewed from the right in FIG. 1.

I claim:

The ornamental design for a pallet, as shown.
